UNITED STATES PATENT OFFICE.

GEORGE R. PYPER, OF SALT LAKE CITY, UTAH, ASSIGNOR TO PYPER ANIMATED SIGN COMPANY, OF SALT LAKE CITY, UTAH, A CORPORATION OF UTAH.

ANIMATED SIGN.

1,382,228.

Specification of Letters Patent. Patented June 21, 1921.

Application filed June 30, 1920. Serial No. 392,954.

To all whom it may concern:

Be it known that I, GEORGE R. PYPER, a citizen of the United States, and a resident of Salt Lake City, in the county of Salt Lake and State of Utah, have invented certain new and useful Improvements in Animated Signs, of which the following is a full, clear, and exact specification.

My invention is concerned with animated signs, and is designed to produce a simple and cheaply constructed sign that can have the subject matter thereof changed or renewed whenever it is necessary or desired without any substantial trouble or expense.

10 To this end, I provide a permanent casing provided with means of access in which is mounted the customary light for illuminating the animated portion, and in the picture frame constituting the front of the casing,

15 I place a screen plate, preferably made of sheet metal, and having its surface that will be back of any portion of a picture that it may be desired to animate perforated by comparatively small closely spaced apertures.

20 In front of this screen plate and firmly secured relative thereto by any desired means is a poster sheet, the front of which is like any ordinary poster, but the back differs therefrom in that it has printed, 25 painted or otherwise secured on its back a layer of opaque material, such as heavy black paint or printers' ink, over that portion of the back corresponding to so much of the poster as is not to be animated. So

30 much of the back as corresponds to the part to be animated is left bare, or if any particular color is to be given to all or any or different parts of the animated portion, it is painted or printed thereon in a thin trans-

35 lucent coating that does not interfere substantially with the passage of light, but merely serves to tint it to the desired color or colors. Within the casing between the light and the portion of the perforated plate

40 covering the animated part of the posters, I mount the animating member, preferably adjustably, so that the same animating member can be used to animate the pictures of different posters. The posters can be print-

45 ed or painted on both sides each side having its own design, as described when they are made, and sent out to where they are to be used, and applied in a few minutes by anybody familiar with the use of animating 50 mechanism.

To illustrate my invention, I annex here- to two sheets of drawings in which the same reference characters are used to designate identical parts in all the figures of which—

Figure 1 is a front elevation of a sign em- 60 ploying my invention, with a portion of the poster torn off from one corner to show the perforated screen plate;

Fig. 2 is a rear elevation of the poster sheet shown in front elevation in Fig. 1 65 detached;

Fig. 3 is a vertical section on the line 3—3 of Fig. 1; and

Fig. 4 is a front elevation of the same with the poster and the perforated screen 70 plate removed.

The main body portion 10 of the casing is made of sheet metal, and is in the form of a generally rectangular metallic box preferably provided with a door 11 in the rear 75 to give access to the interior. The front of the casing has secured thereon to make a picture frame, as it were, a hollow shaped metal molding 12, which has the face portion or ledge 13 bounded on the outer edge 80 thereof by the forwardly extending flange 14, so as to form a seat for the metallic screen plate 15, which is of the proper size to rest in the seat thus provided, and which is provided preferably over its entire sur- 85 face with small closely spaced, preferably regular perforations 16. Placed directly against this screen plate, and secured firmly relatively thereto is the poster 17, which will be of the standard size for which the frame 90 is adapted, and which will have printed on its front surface whatever matter it may be desired to advertise. In the drawing, I have illustrated an automobile tire 18 which is shown as rolling upon road 19 forming a 95 part of the scenic background 20, and it will be understood that the subject matter of the poster may be varied indefinitely so far as carrying out the principles of my invention is concerned, always provided that 100 there is a portion of it to be animated.

The purpose of the animation in the present instance is to produce the illusion of the tire as rolling, and preparatory to this end, all of the back 21 of the poster that is ex- 105 posed to the animating light 43 in the rear, except the generally elliptical portions 22 and 23, and the partial ellipses 24, 25, 26, 27, 28 and 29, is heavily coated by printing or painting with a black pigment, or some 110

other similar hue which serves to absorb all the light striking it. The parts 22 to 29, which are not so coated with the black pigment may be left bare on the back of the poster or may be covered with a light coating of any desired translucent coloring matter, so that the light can pass therethrough.

The animating element consists of a metallic disk 30 having the regular radial 10 slots 31 therein extending from near the center to near the periphery, and having the hub 32 by which it is journaled on the bearing bolt 33 secured in the bearing sleeve 34 of the arm 35 pivotally secured by the 15 bolt and wing nut 36 in any desired adjustment upon the outer end of the arm 37, which in turn is similarly secured by the bolt and wing nut 38 in any desired position of adjustment on the arm 39 supported in 20 any suitable manner from the inside of one side of the casing 10. To rotate the animating disk 30 at any desired speed, I mount in the casing a small electric fan 40, which is preferably adjustably supported on 25 the bracket 41, which in turn may be adjustably supported on the side of the casing in any desired manner, so that the blast of air from the fan may be directed against the vanes 42 secured to and projecting outward 30 from the rear of the disk 30. By this means, the animating disk may be adjusted to any needed position within the casing, and the fan properly placed relative to one side thereof so as to cause the desired rotation 35 above the animating member, the speed of which can be controlled by regulating the speed of the fan 40 in the customary manner.

The illumination for the animated portion 40 is furnished by the powerful incandescent bulb 43 which is mounted in a socket 44 supported by the arm 45 which is adjustably secured in any desired position on the end of the arm 46 by the bolt and wing nut 47. 45 The arm 46 in turn is adjustably supported at its inner end on a bracket 48, seen in dotted lines in Fig. 3, corresponding to and preferably in alinement with the bracket 39 for the animating disk. The light will be so 50 adjusted that the rays from it will be thrown through the slits 31 and through the perforations 16 back of the portions 22, 23, 24, 25, 26, 27, 28 and 29, the axis of the disk being at the center of the tire, as indicated 55 in Fig. 1, so that the effect of the animation is to cause a series of waves of light to traverse the tire 18, and thus give it the appearance of movement.

As a convenient means for securing the 60 poster against the perforated plate 15, I may employ the clamping member 49, which may be made of strips of angle iron of the proper size and shape to register with the surface 13, and which is preferably held in place by 65 the screws 51 passed through holes in this

member 49 and in the edges of the poster and other apertures 50 in the edge of the perforated screen plate 15 and screwed into the edge of the frame 10 and the adjacent portion of the molding 12.

When the poster is to be replaced, it will be obvious that all that has to be done is to remove the screws 51, the clamping member 49 and the poster, and to replace it by a fresh one. If the poster is of a different 75 design, so that the animating mechanism has to be adjusted to a new position, the perforated screen plate may also be removed and the necessary adjustment of the disk 30, the fan 40 and the light 43 made, after which the 80 screen plate will be returned, and the poster will be put in place and secured as before. It will of course be understood that if the screen plate were permanently secured in place or could not be conveniently removed, 85 these adjustments might be made through the door 11.

While I have shown and described my invention as embodied in the form which I at present consider best adapted to carry 90 out its purposes, it will be understood that it is capable of modifications and that I do not desire to be limited in the interpretation of the following claims except as may be necessitated by the state of the prior art.

What I claim as new, and desire to secure by Letters Patent of the United States is—

1. In an animated sign, the combination with a frame, of a plate supported in the front thereof and having relatively small 100 closely spaced perforations therein, a poster sheet securely held in front of the same and having between it and the perforated plate a layer of opaque material corresponding to so much of the front of the poster as is not 105 to be animated, a light back of the perforated plate, a movable animating member mounted between the light and the part of the poster to be animated, and means for moving the animating member.

2. In an animated sign, the combination with a frame, of a plate supported in the front thereof and having relatively small closely spaced perforations therein, a poster sheet securely held in front of the same and having laid on its back a layer of opaque 115 material corresponding to so much of the front of the poster as is not to be animated, a light back of the perforated plate, a movable animating member mounted between 120 the light and the part of the poster to be animated, and means for moving the animating member.

3. In an animated sign, the combination with a frame having a plate supporting 125 ledge bounding the front thereof, of a plate supported on said ledge and having relatively small closely spaced perforations therein, a poster sheet in front of the same and having between it and the perforated 130

- plate a layer of opaque material corresponding to so much of the front of the poster as is not to be animated, a clamping member corresponding in outline to the ledge of the frame resting against the edge of the poster, screws passing through the clamping member, poster and perforated plate into the frame ledge, a light back of the perforated plate, a movable animating member mounted between the light and the part of the poster to be animated, and means for moving the animating member.
4. In an animated sign, the combination with a translucent poster sheet having display matter printed on one side and on the other an opaque design corresponding to so much of the display matter on the front as is not to be animated, of means for supporting said poster with its display side exposed, an artificial light on the other side of the poster, an animating mechanism interposed between the light and a part of the poster to be animated, and means to move said animating mechanism.
5. In an animated sign, the combination with a frame, of a plate supported in the front thereof and having relatively small, closely spaced perforations therein, a poster sheet securely held in front of the same, a light back of the perforated plate adapted to throw rays through all the perforations, an animating member between the light and the plate, a layer of opaque material corresponding to so much of the poster as is not to be animated interposed between it and the animating member, and means for moving the animating member.
6. In witness whereof I have hereunto set my hand and affixed my seal this 28th day of June, A. D. 1920.
- GEORGE R. PYPER. [L. S.]
